TENT

Arthur J. Kirkham, 5336 Avalon Drive,
Murray, Utah 84107

Filed June 27, 1966, Ser. No. 2,831

Term of patent 14 years

(CL D88—3)

FIG. 1.

FIG. 3

FIG. 2

FIG. 4

FIG. 5

FIGURE 1 is a perspective view of a tent showing my new design;

FIGURE 2 is a fragmentary side elevational view of the tent wall window awning as seen at the left end of FIGURE 1;

FIGURE 3 is a fragmentary top plan view of the left end of FIGURE 1;

FIGURE 4 is an elevational view as seen from the left of FIGURE 1; and

FIGURE 5 is a sectional view taken along line 5—5 of FIGURE 1.

The dominant features of the design reside in the full line portions of the drawing, it being understood that the shading in FIGURES 1—5 represents fabric which is continuous.

The broken line showing of the tent has been omitted from FIGURES 2—5 for convenience of illustration.

My design is characterized in that the tent wall window awning is directly adjacent and shields a generally triangular window having upwardly converging side edges, the window awning being held generally taut without

staked guy ropes and comprising two downwardly divergent cantilevered triangular pieces joined along their respective bases to form a gable ridge line at the top of the triangular window, the triangular pieces being individually downwardly convergent, to a point, closely adjacent and at least partly coextensive with respective side edges of the window.

I claim:

The ornamental design for a tent, substantially as shown and described.
